UNITED STATES PATENT OFFICE.

MICHAEL F. KIDD, OF BALTIMORE, MARYLAND.

PEA-SHELLER.

SPECIFICATION forming part of Letters Patent No. 337,960, dated March 16, 1886.

Application filed July 14, 1885. Serial No. 171,631. (No model.)

To all whom it may concern:

Be it known that I, MICHAEL F. KIDD, a citizen of the United States, residing at Baltimore, in the State of Maryland, have invented certain new and useful Improvements 5 in Pea-Shellers, of which the following is a specification, reference being had therein to the accompanying drawings.

My invention relates to improvements in pea-shellers in which the hulls of green peas are removed and separated from the same. I accomplish this result by mechanism illustrated in the accompanying drawings, in which—

Figure 1 is a vertical section through the 15 device; Fig. 2, a top view of the rotating or under disk; Fig. 3, a section view of one of the pins, showing the elastic covering; and Fig. 4, a section view of a pin consisting wholly of elastic material.

Similar letters refer to similar parts throughout the several views.

The letter A designates the frame of the machine, which, as here shown, is of a conical form, with a receptacle, a, in its base for the 25 peas after they are shelled, and is so arranged that it may be slid in or out, as desired, and by which the peas are removed.

To the frame A is attached a circular hopper, B, which directs the peas as they drop 30 from the screen b into the receptacle a, they passing into the same through the opening c in the frame.

To the top of the frame A is secured rigidly a shaft, d, forming a trunnion on and around 35 which the under disk, C, freely rotates, and to the top end of which is attached the upper and stationary disk, D, by means of a cross-beam, e, which extends across the central opening, f, and is secured to the shaft d and disk D by 40 any suitable means, thereby holding the disk D, the shaft d, and the frame A rigidly together.

On top of the disk D is placed and secured a feeding-hopper, g, which encircles the opening f, and which directs the pea-pods into the 45 said opening as they are fed into the machine.

To the under side of the disk D is secured a series of pins, h, which project downward, with their lower ends nearly touching the upper surface of the lower disk, C, and which 50 are arranged in a series of different-diameter circles in such a position that they are and

will be in circles intermediate in relation to the pins in the lower rotating disk, C.

To the periphery of the disk D is secured a 55 cylindrical band, i, which projects downward and overlaps the lower disk, C, the function of which is to retard and direct the peas and pods to the screen b as they are thrown outward from between the disks by the centrifugal force. The under disk is slightly smaller in diameter than the upper one, by which the circular opening k is formed, and through which the peas and pods pass as they fall on the screen. The lower and rotating 60 disk, C, is arranged to rotate freely on the shaft d by being secured to the loose sleeve l, which is provided with a pulley, m, and by which it and the disk C are driven by a belt connected with suitable driving mechanism. 70

To the upper surface of the disk C are arranged pins h', which project upward, and which are arranged like those on the disk D, but in circles of different diameters thereto, so that they will move in circles intermediate 75 in relation to the ones in the upper disk, as above stated, thereby disintegrating the pea-pods and freeing the peas as they are passed therebetween by the centrifugal force of the lower disk, C.

In the center of the disk C, and around the shaft d, is arranged a cone, n, the tendency of which is to force the pea-pods outward and between the pins h and h' as they are fed to the 80 machine.

To the under surface of the disk C is attached a cylindrical screen, b, which rotates with the disk, and which separates the peas from the pods by the former passing through the holes therein, which are of a sufficient size to admit 90 the same, the pods passing off from its periphery, and which are facilitated therein by having pieces of sheet metal or brushes O placed at a tangent to the center of the machine and secured to the upper and stationary disk, D. (See dotted line, Fig. 2.)

The pins h and h' are either made of a hard substance—such as iron or wood—and covered with rubber or other elastic material, as shown in Fig. 3, or wholly of elastic material, so that 100 in either case they present an elastic surface, but are of sufficient stiffness to break or disintegrate the pods, though the first-named construction is preferable. The reason of hav-

ing an elastic surface is, that while the pods are very tough the peas are easily bruised or "scalped." Therefore it is very important, and almost essential, to have the pins constructed as above described, the number of which and the number of circles being regulated according to the capacity of the machine. The opposing rubber surfaces, moreover, grasp the pods between them, and the disintegrating effect is thereby increased.

Either or both the disks may be made to rotate; but I prefer the lower one only to do so, as the centrifugal force is more effective when the machine is arranged that way, and instead of the disks being flat they may be slightly concave and convexed or conical and produce the same results.

In operating the machine the disk C is rotated at rather a high speed, by which the centrifugal force is made available to feed the peas and pods through and from between the disks. The pods are then placed in the feeding-hopper, from which they pass down between the disks, the cone n starting them outward, or directing them into and between the pins h and h', which as they (the pods) pass outward are disintegrated by coming in contact with the stationary and moving pins, which release the peas, the whole (peas and pods) passing out through the opening k and falling on the rotating screen b, which separates the peas from the pods, the former passing down through the screen b into the receptacle a, and the latter being thrown off from the outer edge of the screen, either by the centrifugal force or by the device O, secured to the disk D, by coming in contact therewith.

By this device all the peas are removed from the pods, from the smallest to the larger ones, and in a superior manner, being free from any 40 bruises, and in a cleanly condition.

Having fully described my invention, what I claim, and wish to secure by United States Letters Patent, is—

1. In a pea-sheller, the combination of the feed-hopper g, the disk C, the disk D, and the interlapping elastic-surfaced pins h and h', secured to the said disks, whereby the pea-pods are disintegrated and the peas when released therefrom are prevented from being injured. 45 5c

2. In a pea-sheller, the combination of the disks C and D, the interlapping elastic-surfaced pins h and h', secured to the said disks, the feed-hopper g, arranged to deliver the pea-pods in the center of the disks, and the band i, secured to the disk D, for the purpose as herein set forth. 55

3. The combination of the disks C and D, the pins h and h', secured to the disks and provided with an elastic covering, the feed-hopper g, and a screen secured to and extending 6c around the edge of the disk C, as herein set forth.

4. In a pea-sheller, the combination of the disks C and D, provided with interlapping elastic-surfaced pins h and h', for the purpose 65 set forth.

In testimony whereof I affix my signature in presence of two witnesses.

MICHAEL F. KIDD.
